It is hereby certified that in Letters Patent No. 411,554, granted September 24, 1889, upon the application of George C. Macsters, of Brooklyn, N. Y., for an improvement in "Dulcetinas," an error appears in the printed specification requiring correction, as follows: In line 34, page 1, the word "insular" should read *circular*; and that the Letters Patent should be read with this correction therein that the same may conform to the record of the case in the Patent Office.

Signed, countersigned, and sealed this 8th day of October, A. D. 1889.
